UNITED STATES PATENT OFFICE

MARTIN KAHR, OF FRANKLIN, PENNSYLVANIA, ASSIGNOR TO FRANKLIN VALVELESS ENGINE COMPANY, OF FRANKLIN, PENNSYLVANIA, A CORPORATION OF PENNSYLVANIA

POWER PLANT FOR DRILLING APPARATUS

Application filed March 25, 1926. Serial No. 97,417.

This invention relates to internal combustion engine power plants and particularly to apparatus of this type including a plurality of engines.

5 In power plants for rotary drilling apparatus, for example, one engine is required to operate the rotary drill. At the same time the apparatus must be lubricated or "slushed", and another engine is ordinarily required to operate 10 the slush pumps. After a few hours the drill bit becomes dull and must be replaced, and for this, or for other, purposes the drill pipe must be pulled out frequently. This operation requires a great deal more power than 15 the drilling and the drilling engine has heretofore been made large enough to handle this overload. At the same time, however, the slush pumps are idle and the engine normally operating them is available for other 20 uses. On the other hand, when the drill becomes clogged, or for other purposes, a great amount of slush fluid under high pressure is desired, and the slushing engine is thus required to be capable of handling considerable 25 overloads while at the same time the drilling engine is idle.

An object of this invention is to enable the use of engines designed for the normal conditions of load of the driven machines, that 30 is smaller or lower-powered engines than heretofore used, for either or both of the above purposes, and at the same time to have available the excess power needed for operating either of the machines driven from the respective engines when additional power is required to meet a substantial overload.

Another object of the present invention is to provide means whereby two or more engines may be operated and controlled independently, or may be combined as a single power unit.

A further object of this invention is to provide means whereby two or more engines may be operated and controlled independently 45 from a distant control station, or may be combined and controlled conjointly from such control station.

One embodiment of the invention has been illustrated in the accompanying drawings, 50 but it is to be expressly understood that these

drawings are for purposes of illustration only, reference being had to the appended claims for a definition of the limits of the invention.

In the drawings,—

Fig. 1 is a diagrammatic illustration of a power plant for rotary drilling apparatus;

Fig. 2 shows one of the engines of said power plant;

Fig. 3 is a detail view showing the connections between the control means of the engines;

Fig. 4 is a detail showing of the operating lever for said control means; and

Fig. 5 is a detail showing of a part of the connections between said lever and said control means.

Referring to the drawings, wherein like reference numerals indicate like parts, Fig. 1 illustrates diagrammatically a power plant 70 shown as applied to rotary drilling apparatus and comprising two internal combustion engines 1 and 2 of any suitable type. Engine 1 is adapted to operate the rotary drilling apparatus 3 by any suitable means as a chain or 75 belt 4 driving a shaft 5 supported in suitable bearings 6, 6'. The shaft 5 is provided with a reversible clutch mechanism 7 of any known type and with suitable belt or chain connections 8, 8' whereby a line shaft 9 may be rotated in either direction. Shaft 9 is connected by means of a belt 10 with the rotary drill 3. Slush pumps 11, 11' of any suitable type are operated by engine 2 by means of suitable connections 12 and 12'. Means are preferably provided whereby the engines 1 and 2 may be respectively controlled from the drilling apparatus, as telegraph wheels 13 and 14 which are operatively connected with the control mechanisms of said engines, as described hereinafter.

Engines 1 and 2 are preferably of the type illustrated and described in my co-pending application Serial No. 92,573, filed March 5, 1926, and are provided with the type of control means disclosed in this application. Fig. 2 illustrates such an engine having a casting 15 and lay shaft 16. A pump 17 of any suitable type is provided for feeding fuel to said engine and the amount of fuel may be regu- 100

lated by suitable means such as a valve 18, having a valve stem 19, positioned in the supply line to the engine. A lever 20 has a floating fulcrum 21 and engages the valve stem 19 of the valve 18, being adapted to operate the latter at a suitable point in the stroke of the piston when actuated by a push rod 22 operated in any suitable way. As the push rod 22 is raised, it engages the outer end of lever 20 and rotates the latter about its fulcrum 21, thereby operating the valve 18 and cutting off the supply of fuel to the engine.

The speed of the engine is regulated by varying the position of the fulcrum 21, which is supported on a plunger or piston member 22' operating in a dash pot 23 which serves to damp the movement of the fulcrum. Means are provided for regulating the position of this fulcrum, as described in my prior application, including an L-shaped arm 24 connected to the plunger 22' and engaging the free end of a lever 25, the other end of said lever being suitably pivoted to the engine casting. Intermediate its ends, lever 25 is connected at 26 to a governor spindle operated by the fly balls 27. As the speed increases, balls 27 are forced outwardly, raising the governor spindle and the lever 25, and thereby raising the fulcrum 21. As fulcrum 21 is raised, push rod 22 will operate the valve 18 at an earlier point in the stroke, thereby decreasing the amount of charge admitted to the engine cylinder and decreasing the speed.

The upper end of the governor spindle 28 slides in the interior of a tubular member 29 having threaded engagement with the casing of the engine. The upper end of said tubular member is closed by means of a screw 30 and resilient means such as a spring are interposed between the lower end of the screw 30 and the upper end of the governor spindle 28. The telegraph wheel 13' is secured to the upper end of member 29 and is connected by means of rope or cord with the telegraph wheel 13. When the wheels 13 and 13' are rotated so as to screw the member 29 into the casing, the tension of the spring is increased and the speed at which the governor spindle 28 will operate to raise the fulcrum 21 is increased correspondingly. Conversely, when the telegraph wheels 13 and 13' are rotated in the reverse direction, the tension of the spring is decreased and the speed at which the governor spindle 28 becomes operative is decreased correspondingly. By these means the speed may be controlled from the drilling station.

In conformity with the present invention, means are provided whereby the combined power of the two engines may be made available to operate either the drilling mechanism or the slush pumps. When combined, either engine may serve as a supplementary source of power or "booster" for the other engine according to the conditions of operation. In

order to suitably connect the two engines mechanically, the shaft of engine 2 is here shown as extended by a portion 32 (Fig. 1) which is either integral with said shaft or suitably secured thereto, and which is connected at its other end with a coupling member 33 of any suitable type. The latter is operatively connected in any way with the shaft of engine 1. When the coupling is engaged, the two engines operate as a single power unit; when disengaged, they may be operated independently. Suitable means are likewise provided whereby the control mechanisms of the several engines may be combined and operated as a single control system, preferably from the drilling station. In the form shown, engines 1 and 2 are provided with rock shafts 34 and 34' supported in any suitable manner on the engine structure, said shafts being provided with suitable arms 35, 35' which carry in their outer ends means such as the screws 36, 36' each engaging the upper portion of the plunger 22'. The screws 36, 36' may be locked in position by locking nuts as 37, Fig. 2.

Preferably shafts 34 and 34' are each provided at one end with a universal joint 38, 38' of any suitable type, and means are provided for connecting said universal joints together which, as shown, include a shaft 39 connected at one end to universal joint 38 and having on its other end a splined sleeve 40 which is attached thereto in any suitable way, as by means of a taper bolt 41 and nut 42. The free end of splined sleeve 40 is adapted to receive the outer end of universal joint 38' which is similarly splined, and by this means a slidably coupling is formed which connects the shafts 34 and 34'. The universal joints and slidably coupling are provided in order to allow for poor alinement of the various parts, which may often be the case.

In order to enable the drill operator to control both engines conjointly from the drilling station, means are preferably provided for operating the combined control mechanisms from said station. In the form shown, one end of shaft 34 is tapered to form a spindle for the end of a suitable arm 43 (Fig. 5). The arm 43 is secured on the end of the shaft as by means of a nut 44 and is keyed thereto by a suitable member 45. The arm 43 preferably extends upwardly and is forked at its upper end, said forks supporting on their inner sides guide blocks 46, 46', as by means of bolts 47, 47'. The inner faces of the blocks 46 and 46' are provided with notches or grooves 48 which form a substantially circular opening extending between said blocks. A rod 49 extends through this opening, having on one end a nut or cap 50, and resilient means, preferably a coil spring 51, are interposed between the cap 50 and the blocks 46, 46'. Rod 49 is thus slidably between said blocks and may also swivel in

its support. The other end of rod 49 is provided with an eye 52 in which is inserted one end of a rope or cord 53 leading to the drilling station. The other end of the cord 53 is connected to one end of a bell crank lever 54 located at the drilling station, said lever being provided with a suitable latching mechanism 55 of any known type. The movement of lever 54 is limited in one direction by a stop 56 and in the other direction by an adjustable stop 57.

Normally, both engines run independently and are controlled from the drilling station by means of the telegraph wheels 13 and 14.

15 When it is desired to combine the engines to operate as a unit, the telegraph wheels 13' and 14' are first turned to their upper position, that is for minimum speed. The control lever 54 is likewise moved to its minimum speed position, i.e., against the stop 56. Both engines are now running at minimum speed, controlled by the independent governing devices. The rope 53 is now connected between rod 49 and lever 54 and is adjusted as by 20 means of a turn buckle to the proper length in order to give the arm 43 the desired position. Coupling 33 is engaged, connecting the two engines, and coupling 40 is adjusted to connect the shafts 34 and 34' together. Adjusting screws 36 and 36' are now turned 25 down until they just touch the upper surface of each plunged 22', and are locked in that position by means of lock nuts.

To speed up the engines, lever 54 is moved 30 downward toward the stop 57. This movement acts through rod 49 and spring 51 to rotate the arm 43 and with it the rock shafts 34, 34', thereby lowering the fulcrums 21, 21' and causing the fuel valves 18, 18' to operate 35 at a later point in the stroke of the piston, thus admitting more fuel to the engines. In other words, movement of lever 54 toward the stop 57 causes the engines to speed up. Maximum speed may be adjusted by moving 40 the adjustable stop 57. The spring 51 may be adjusted to give the engine any desired range of speed within the limits of movement of the lever 54.

When the lever 54 is moved toward stop 45 56, thereby slackening the line 53, the rock shafts 34, 34' are rotated in the reverse direction by any suitable means such as levers 58, 58' secured to said shafts in any suitable manner, and having springs 59, 59' interposed between the outer ends of said levers and the engine structures. These levers also serve to take up any lost motion in the connections between the governing devices.

It will be apparent that by means of this 50 device, the two engines may be operated independently and independently controlled from the drilling station, or they may be combined and operated as a single power unit and controlled simultaneously from the 55 drilling station. In many cases the use of

this invention will effect considerable savings in cost of the operating plant. In rotary drilling apparatus, for example, the engine operating the drill is normally required to be approximately twice as large as is necessary to operate the drill in order to take care of the temporary overloads, such as occur in pulling out the drill bit. By combining the power of the two engines, it is therefore possible to effect a great saving in 60 the size and cost of the drilling engine, and a corresponding saving in the cost of its operation. Similarly, the engine operating the slush pumps is required to be capable of handling considerable overloads, and by employing the drilling engine as an auxiliary or booster engine, substantial savings may be effected in the cost of this equipment.

While only one embodiment of the invention has been illustrated in the accompanying drawings, it will be apparent that the invention is not limited to this embodiment but is susceptible of a variety of expressions, and also that changes may be made in the arrangement and details of the parts without departing from the spirit of the invention. Reference is therefore to be had to the appended claims for a definition of the limits of the invention.

What is claimed is:

1. In combination with a plurality of internal combustion engines each having speed regulating means, a rock shaft for each of said engines having a rocker arm operatively engaging said regulating means, means for connecting said shafts including a universal joint and a slidable coupling, an arm secured to one of said shafts, and means operatively connected to said arm for rotating said shafts from a distance.

2. In combination with a plurality of internal combustion engines having speed regulating means, a rock shaft operatively connected with said speed regulating means, an arm on said shaft having a bifurcated end, blocks supported by said bifurcations and having similarly disposed grooves on their interior faces, a rod extending through the opening formed by said grooves, resilient means interposed between said rod and said blocks, and means attached to said rod for rotating said shaft from a distance.

3. In combination with a plurality of internal combustion engines each having speed regulating means, means including a rock shaft in operative engagement with each of said regulating means, means for operatively connecting said rock shafts, means normally tending to rotate said shaft in one direction including a lever operatively connected to said shaft and resilient means actuating said lever, and means for rotating said shaft in the opposite direction from a distance.

4. In combination with a plurality of internal combustion engines each having speed

regulating means, means including a rock shaft in operative engagement with each of said regulating means, means for operatively connecting said rock shafts, a lever operatively connected to said shaft, resilient means tending to rotate said lever and shaft in one direction, an arm secured to said shaft, and means including a resilient member operatively engaging said arm for rotating said 10 shaft in the opposite direction.

5. In rotary drilling apparatus including drilling mechanism and pumping mechanism, an engine for operating each of said mechanisms, and means for combining said 15 engines to operate either of said mechanisms conjointly.

6. In rotary drilling apparatus, in combination with the rotary drill and slush pumps thereof, an engine operatively connected to said drill, a second engine operatively connected to said slush pumps, and means for connecting either of said engines to the other engine to operate conjointly with the latter. 20

7. In rotary drilling apparatus including drilling mechanism and pumping mechanism, a pair of internal combustion engines, each of said engines normally operating one 25 of said mechanisms, means for controlling said engines independently, means for combining said engines to operate either of said mechanisms conjointly, and means for controlling said engines as a unit. 30

8. In rotary drilling apparatus including 35 a rotary drill and slush pumps, an internal combustion engine normally operating said drill, a second internal combustion engine normally operating said pumps, means for controlling each of said engines independently from the drilling station, means for combining said engines to operate conjointly either said drill or said pumps, and means for controlling the combined engines as a unit from the drilling station. 40

9. In rotary drilling apparatus including 45 two driven mechanisms, an internal combustion engine for operating each driven mechanism, means for disconnecting either engine from its driven mechanism, and means for combining the two engines to operate the other driven mechanism jointly. 50

In testimony whereof I have signed this specification.

MARTIN KAHR.
